UNITED STATES PATENT OFFICE.

CHARLES J. HAUCK, OF BROOKLYN, E. D., NEW YORK.

DESIGN FOR TOBACCO-BOX.

Specification forming part of Design No. **7,183**, dated February 17, 1874; application filed January 23, 1874.
[Term of Patent 14 years.]

To all whom it may concern:

Be it known that I, CHARLES J. HAUCK, of Brooklyn, E. D., in the county of Kings and State of New York, have invented a new and original Design for a Tobacco-Box; and I do hereby declare the following to be a full, clear, and exact description thereof, which will enable those skilled in the art to make and use the same, reference being had to the accompanying drawing forming a part of this specification, in which drawing—

Figure 1 represents a plan view of this invention. Fig. 2 is a side view of the same.

Similar letters indicate corresponding parts.

This invention consists in the design, for a tobacco-box, of an oval body and lid, and of an offset edge on said lid, arranged in such a manner that when the box is closed the whole presents a novel and elegant appearance.

The letter A designates the body of my to-

bacco-box, which is oval; and B is its top lid, corresponding thereto. Each of these parts is raised or segmental, and the body A is provided with a rounded edge, a. The lid B is provided with a bead or offset, b, on its edge, which, when the box is closed, lies close on the rounded edge a of the body.

By these means a novel and elegant appearance is imparted to my box, which can be readily distinguished from other articles of the same nature.

What I claim as new, and desire to secure by Letters Patent, is—

The design for a tobacco-box, as shown and described.

C. J. HAUCK.
